UNITED STATES PATENT OFFICE.

JOHN G. COLLISON, WALTER N. FRANK, AND HARRY M. FILBERT, OF DAYTON, OHIO,
ASSIGNORS, BY MESNE ASSIGNMENTS, TO THE GROLAN MANUFACTURING COMPANY, OF DAYTON, OHIO, A CORPORATION OF DELAWARE.

PRINTING MACHINE.

Application filed March 30, 1922. Serial No. 548,201.

To all whom it may concern:

Be it known that we, JOHN G. COLLISON, WALTER N. FRANK, and HARRY M. FILBERT, citizens of the United States, residing at Dayton, in the county of Montgomery and State of Ohio, have invented certain new and useful Improvements in Printing Machines, of which the following is a specification, reference being had therein to the accompanying drawing.

Our invention relates to a printing machine and in particular to a machine for and method of off-set printing.

This application is filed in place of the joint application, Ser. No. 521,673, filed December 12, 1921, by John G. Collison and Walter N. Frank, two of the inventors in the present case.

The particular adaptation shown in this application is that of printing dials for counters, gauges and the like, but it will be understood that our invention is adaptable to a variety of other applications.

It is our object to provide a machine which will print from a flat bed of type or an electrotype or other similar means. It is our object to provide a machine for the transmission of the printed impression through the medium of a yielding surface so as to secure the effects of so-called off-set printing and to insure the transfer to surfaces of the desired impressions which could not be ordinarily secured by direct printing from the type or metal upon the particular surface desired, such as an enamel or metal surface or a highly porous surface.

It is our object to provide a method and machine of the character described for the transmission of just a sufficient amount of ink to the surface to be printed in the desired configurations so that not only ordinary surfaces but highly delicate and porous surfaces can be properly printed with the sufficient amount of printing ink or other material used without blurring or running.

It is a further object to provide a machine which will be easily inked, which will be susceptible of the greatest accuracy of impression and alignment of the impressions for gauge dials and the like and which will

permit of the ready renewal of the type matter and the use of cheap flat electrotypes or other plates.

It is a further object of our invention to provide for the ready mounting of the material to be printed and the demounting of it to insure rapidity of operation. It is an additional object of the invention to provide such a construction that the greatest accuracy possible will be insured by the elimination of lost movement so that each duplicate registration will be exactly like every other of the same kind upon the same material.

In the particular adaptation shown here we have illustrated a machine for printing the dials on gasoline gauges, such as used on automotive equipment.

In our particular adaptation here shown we have illustrated by a single unit which, as realized, may be duplicated or added to so that each unit may print a separate color. It is a further object to provide a machine which may be readily re-inked, the type matter readily removed, the matter to be printed may be readily put in printed position or removed therefrom and in which the amount of inking may be suitably controlled.

Referring to the drawings:

Fig. 1 is a side elevation of our machine;

Fig. 2 is an end elevation of our machine;

Fig. 3 is a plan view of a modified inking mechanism;

Fig. 4 is a side elevation of Fig. 3.

Referring to the drawings in detail, 1 is a base of the machine upon which is mounted an upstanding rib or wall 2. This wall supports a bearing 3 for the main actuating shaft 4 which is actuated by a handle 5 or as preferred by any suitable power such as an electric motor. The movement of the handle 5 and consequently of the shaft 4 is limited as the handle is reciprocated back and forth by the stop pins 6. Upon the wall 2 is mounted a bed 7 fastened thereto by bolts 8. Upon the bed 7 is mounted a type support or carrier 10. This type support is embraced between the plates 11 and 12 bolted to 7 by the bolts 9. Carrier 10 is adapted to slide between and beneath these plates 100

upon the bed 7. This reciprocatory movement of the type carrier 10 which carries the type 13 is secured through a rack 14 retained by a screw 15 upon the side of the type carrier 10. This rack is in engagement with a master gear 16 which is mounted upon the shaft 4 that is actuated by the handle 5.

Also mounted on the shaft 4 is a transfer wheel or drum 19, which may be of any suitable material, such as rubber or one of the compositions in the art. This drum is of such diameter and so positioned as to engage the type 13 carried by the support 10 as the latter reciprocates on the bed 7.

15 Formed on the base 1 is a bearing 1^a through which passes a shaft 1^b, one end of the shaft projecting in front of the bracket 2 and carrying an arm 28 provided at its upper end with a bearing 28^a through which 20 passes a shaft 28^b secured against longitudinal movement in one direction in the bearing by means of a washer 28^c and nut 28^d. On this shaft 28^b is fixed a gear 17 which bears against the other end of the bearing 28^a and 25 prevents movement of the shaft in the opposite direction. This gear 17 meshes with the gear 16 so that as the latter is rotated by the crank handle, the shaft 28^b will be rotated. On the inner end of the shaft 28^b there is 30 also provided a head 18 adapted to fit within the drum or cylinder 18^a which is to receive on its periphery the article to be printed by the roller 19. A tension spring 27 has one end attached to the arm 28 and its other end attached to an opening 27^a fixed in the bracket 2. This tension spring is so positioned as to constantly urge the arm 28 and the head 18 in the direction of the transfer roller 19. Projecting from the arm 28 is a 35 bracket 28^e carrying a roller 28^f which is held by the action of the spring 27 to bear against a cam 36 fixed on the shaft 4. This cam is so shaped and positioned that the articles to be printed will be brought against 40 the transfer roller 19 only at the proper time to have the impression transferred from that roller to the surface of such articles, the cam being arranged to hold the arm 28 away from the transfer roller 19 at other times.

45 On the shaft 1^b is also mounted a bracket 1^e through which passes a bolt 1^d on which is mounted an arm 1^e provided at its upper end with a handle 32 which projects from the side of a bearing 33 supporting a shaft 50 33^a having at one end a head 34 adapted to bear against the flat end of the drum or cylinder 18^a to be printed when the latter is on the mandrel or support 18. This arm 1^e is normally urged in the direction of said 55 mandrel by means of a coil spring 29 which is secured at one end to a pin 30 projecting from the bearing 1^d, and at its other end to a pin 31 projecting from the arm 1^e. By this means the cylinders or drums to be printed 60 will be securely held on their mandrel while

rotating freely with such mandrel when the gears 16 and 17 are in mesh and the shaft 28^b is rotated.

In the operation of the device provision is made for inking the type and to this end 70 there is provided a shaft 22 which is fixed at one end in the bracket 2 and which supports a pair of bent arms 21 each having a slot 21^a therein. In the slots 21^a are mounted bearings 21^b which support a shaft 26 75 carrying an ink supplying roller 23. Journalled on a shaft 21^c also mounted in the arm 21 is an ink distributing roller 20 against which the roller 23 is held by means of springs 24, each having one end fixed to 80 a pin 25 carried by a respective arm 21, and its other end fixed to a respective bearing 21^b, the springs being tension springs. A pin 21^d serves to limit the downward movement of the roller 20 and holds it in position to engage the type as they pass underneath said roller. In using the device the crank 5 is so positioned as to move the arm 28 away from the shaft 4. The handle 32 is then grasped and the arm 21^e swung backward so that the article to be printed may be slid on the mandrel 18. The handle 32 is then released, whereupon the head 34 clamps the article securely on the mandrel. The handle 5 is then given a complete oscillation 85 in one direction being that shown by the arrow in Figure 1. This moves the type on its bed under the type inking roller 20 and the impression of the type is made on the transfer roller 19 and from there is conveyed to the article 18^a on the drum 18, this taking place by reason of the cam 36 having been rotated at the proper time by the action of the movement of the crank to permit the cam roller 28^f to ride on the low part of the 90 cam, and consequently to permit the article on the drum 18 to bear against the transfer roller. The crank handle 5 is then rotated in the opposite direction until it comes in contact with the other stop pin 6. At this 95 time the high part of the cam will force the arm 28 away from the shaft 4 and by proper manipulation of the handle 32 the arm 1^e is swung back and the printed article removed from its mandrel, an unprinted article being placed in position for the next 100 operation.

In order to insure thorough distribution of the ink in cases where a broader face of type is to be used than a single line for making up legends for dial faces, we employ the mechanism shown in Figures 3 and 4 which takes the place of the inking roller and the attendant mechanism shown at the right hand of Figure 1.

125 In these figures there is illustrated a motor 46 which drives a worm 45 meshing with the worm wheel 44 carried on a shaft 44^a supported in brackets 44^b. On this shaft is also an ink distributing roller 40 and a gear 130

43. This gear 43 meshes with a gear 42 fixed on a shaft 42^a carrying a second distributing roller 39. The gear 42 also meshes with a gear 41 fixed on a shaft 41^a carrying a third ink distributing roller 38 which bears against the fourth distributing roller 37. Extending between the brackets 44^a is a shaft 47 supporting a pair of arms 48 carrying a shaft 49 whereon is mounted the type inking roller 50. On the side of the type support 10 is mounted a cam 51 which engages a roller 52, carried by one of the arms 48 when the type carrier or support is moved in one direction so that the type inking roller 50 is lifted at this time into contact with the fourth distributing roller 37 and receives ink therefrom. As the type carrier 10 moves in the opposite direction the roller 52 passes off of the cam 51 and the type inking roller 50 drops on the type and inks the same. Thus by means of the series of ink distributing rollers a more even supply of ink is obtained.

While we have shown and described certain features as constituting our invention, it will be understood that parts have been shown for purposes of illustration only, and that we do not desire to be limited to such details, as obvious modifications will occur to persons skilled in the art.

Having thus fully described our invention, what we claim as new and desire to secure by Letters Patent, is:—

1. In combination, a type bed carrying type, means for inking said type, means for passing said type bed beneath a yielding impression roller, a support containing a member to be printed, means for holding said member to be printed on said support, means constantly urging said holding means against the member to be printed, and a handle to operate said holding means.

2. In a device of the character described, a transfer roller, a shaft supporting said roller, a support adapted to receive an article to be printed, a shaft carrying said support, a head adapted to retain the article on said support during the printing operation, and a handle to remove said head from engagement with the article being printed to permit its removal from said support.

3. In a device of the character described, a transfer roller, a shaft supporting said roller, a support adapted to receive an article to be printed, a shaft carrying said support, a head adapted to retain the article on said support during the printing operation, a handle to remove said head from engagement with the article being printed to permit its removal from said support, and a handle for operating the shaft carrying said transfer roller.

4. In a device of the character described, a transfer roller, a pair of arms supported for swinging movement and positioned to

have their free ends move toward and from the transfer roller, a pair of aligned shafts journalled in the free ends of said arms, a mandrel on one of the shafts for supporting work to be acted upon by the transfer roller, 70 and a head on the other shaft for clamping said work to said mandrel.

5. In a device of the character described, a transfer roller, a bearing arranged parallel to the axis of said transfer roller, a shaft 75 journalled in said bearing, an arm fixed on said shaft at one end thereof, a bearing at the other end of said arm, said bearing being arranged to move from and toward the transfer roller, means constantly urging said 80 arm towards said transfer roller, a shaft supported in the last mentioned bearing and provided with a work supporting mandrel, a bracket on the other end of the first mentioned shaft and carrying a pivot pin arranged transversely of said first mentioned shaft, a second arm supported at its lower end on said pivot pin and provided with a bearing at its upper end adapted for alignment with the bearing on the upper end of 85 the first arm, a shaft in the bearing at the upper end of the second arm, a clamping head on said shaft engageable with the work on said mandrel and means constantly urging 90 said clamping head toward said mandrel. 95

6. In a device of the kind described, a transfer roller, a bearing arranged parallel to the axis of said transfer roller, a shaft journalled in said bearing, an arm fixed on said shaft at one end thereof, a bearing at the upper end of said arm, said bearing being arranged to move toward and from the transfer roller, means constantly urging said 100 arm toward said transfer roller, a shaft supported in the last mentioned bearing and provided with a work supporting mandrel, a bracket on the remaining end of the first 105 mentioned shaft and carrying a pivot pin arranged transversely of said first mentioned shaft, a second arm supported at its lower end on said pivot pin, and provided with a bearing at its upper end adapted for alignment with the bearing at the upper end of the first arm, a shaft in the bearing at the upper end of the second arm, a clamping 110 head on said shaft engageable with the work on said mandrel, means constantly urging said clamping head toward said mandrel. 115

7. In a device of the kind described, a transfer roller, a bearing arranged parallel to the axis of said transfer roller, a shaft journalled in said bearing, an arm fixed on said shaft at one end thereof, a bearing at 120 the upper end of said arm, a shaft in the bearing at the upper end of the second arm, a clamping head on said shaft engageable with the work on said mandrel, means constantly urging said clamping head toward said mandrel, a shaft supporting said transfer roller, a gear on said shaft, and a gear on the mandrel supporting shaft and adapted to mesh with the gear on the transfer roller supporting shaft upon movement of the first mentioned arm in the direction of the transfer roller. 125

8. In a device of the kind described, a transfer roller, a bearing arranged parallel to the axis of said transfer roller, a shaft journalled in said bearing, an arm fixed on said shaft at one end thereof, a bearing at 130

- the upper end of said arm, said bearing being arranged to move toward and from the transfer roller, means constantly urging said arm toward said transfer roller, a shaft supported in the last mentioned bearing and provided with a work supporting mandrel, a bracket on the remaining end of the first mentioned shaft and carrying a pivot pin arranged transversely of said first mentioned shaft, a second arm supported at its lower end on said pivot pin, and provided with a bearing at its upper end adapted to alignment with the bearing at the upper end of the first arm, a shaft in the bearing at the upper end of the second arm, a clamping head on said shaft engageable with the work on said mandrel, means constantly urging said clamping head toward said mandrel, a shaft supporting said transfer roller, a gear on said shaft, and a gear on the shaft carried by the first mentioned arm and adapted to mesh with the last mentioned gear upon movement of the first mentioned arm in the direction of the transfer roller, means to oscillate the transfer roller and its shaft, a cam device actuated by the oscillation of the shaft supporting the transfer roller and arranged to force the first mentioned arm away from said transfer roller during part of the oscillation, a bed beneath said transfer roller, a type carrier movable along said bed, a rack fixed to said type carrier and meshing with the first mentioned gear, and means supported adjacent said bed for inking the type carried by the type carrier. 50
- 15 55
- 10 60
- 15 65
- 20 70
- 25 75
- 30 80
8. In a device of the kind described, a transfer roller, a bearing arranged parallel to the axis of said transfer roller, a shaft journalled in said bearing, an arm fixed on said shaft at one end thereof, a bearing at the upper end of said arm, said bearing being arranged to move toward and from the transfer roller, means constantly urging said arm toward said transfer roller, a shaft supported in the last mentioned bearing and provided with a work supporting mandrel, a bracket on the remaining end of the first mentioned shaft and carrying a pivot pin arranged transversely of said first mentioned shaft, a second arm supported at its lower end on said pivot pin, and provided with a bearing at the upper end of the first arm, a shaft in the bearing at the upper 85 90
- end of the second arm, a clamping head on said last mentioned shaft engageable with the work on said mandrel, means constantly urging said clamping head toward said mandrel, a shaft supporting said transfer roller, a gear on said shaft, and a gear on the shaft carried by the first mentioned arm and adapted to mesh with the last mentioned gear upon movement of the first mentioned arm in the direction of the transfer roller, means to oscillate the transfer roller and its shaft, a cam device actuated by the oscillation of the shaft supporting the transfer roller and arranged to force the first mentioned arm away from said transfer roller during part of the oscillation, a bed beneath said transfer roller, a type carrier movable along said bed, a rack fixed to said type carrier and meshing with the first mentioned gear, and means supported adjacent said bed for inking the type carried by the type carrier. 70
9. In a printing machine, a base, a type carrying bed slidably mounted thereon, a transfer roller journalled on the base and disposed above the bed, a mandrel for supporting cylindrical objects to be printed, and resilient means for normally urging the mandrel towards the transfer roller to cause such object to yieldably engage the transfer roller. 75
10. In a printing machine, a base, a type carrying bed slidably mounted thereon, a transfer roller journalled on the base and disposed above the bed, a mandrel for supporting cylindrical objects to be printed, and resilient means for normally urging the mandrel towards the transfer roller to cause such object to yieldingly engage the transfer roller, and a common means for rotating the transfer roller and mandrel, and imparting reciprocatory motion to the bed. 80
- 85
- 90
- In testimony whereof, we affix our signatures.
